UNITED STATES PATENT OFFICE.

WILLIAM G. COX, OF CLEVELAND, OHIO, ASSIGNEE, BY MESNE ASSIGNMENTS, TO THE EATON AXLE AND SPRING COMPANY, OF CLEVELAND, OHIO, A CORPORATION OF OHIO.

DESIGN FOR A FACEPLATE FOR AN AUTOMOBILE BUMPER.

Application filed September 10, 1921. Serial No. 499,839. Term of patent 7 years.

To all whom it may concern:

Be it known that I, WILLIAM G. Cox, a citizen of the United States, residing at Cleveland, in the county of Cuyahoga and State of Ohio, have invented a new, original, and ornamental Design for a Faceplate for an Automobile Bumper, of which the following is a specification, reference being

had to the accompanying drawing, forming part thereof, in which the figure is a front view of a faceplate for an automobile bumper showing my new design.

I claim:

The ornamental design for a faceplate for an automobile bumper, as shown.

WILLIAM G. COX.
